SIDE WALL AND FENDER PROTECTOR

Donald A. Swauger, 11528 Saratoga Ave.,
San Jose, Calif. 95129

Filed Oct. 18, 1966, Ser. No. 4,321

Term of patent 14 years

(Cl. D14—6)

FIG. 1 is a side view of a side wall and fender protector embodying the present design.

FIG. 2 is a side view of the side wall and fender protector of FIG. 1 at larger scale broken away to indicate indeterminate length.

FIG. 3 is an elevational view of the bottom edge of FIG. 2, the upper edge thereof being identical but reversed.

FIG. 4 is a bottom plan view of FIG. 3.

FIG. 5 is an end view of FIG. 3 as seen from the left-hand end therein.

FIG. 6 is an end view of FIG. 3 as seen from the right-hand end therein.

The automobile shown in broken lines in FIG. 1 is included for illustrative purposes only.

I claim:

The ornamental design for a side wall and fender protector for vehicles, as shown and described.
